UNITED STATES PATENT OFFICE.

WILLIAM E. THOMPSON, OF PINCKNEY, MICHIGAN.

CAR-COUPING.

SPECIFICATION forming part of Letters Patent No. 241,894, dated May 24, 1881.

Application filed March 8, 1881. (No model.)

To all whom it may concern:

Be it known that I, WILLIAM E. THOMPSON, of Pinckney, in the county of Livingston and State of Michigan, have invented an Improvement in Railroad-Car Couplings, of which 5 the following is a specification.

The nature of my invention relates to certain new and useful improvements in the construction of coupling devices for securing rail- 10 way-cars together.

The invention consists in the peculiar construction, arrangement, and operation of the various parts, as more fully hereinafter de- 15 scribed.

15 In the accompanying drawing, which forms a part of this specification, my invention is shown in a central longitudinal section.

A represents a flaring-mouthed draw-bar and buffer-head, and B a hollow section of the 20 draw-bar proper. C is a rod surrounded by a coil-spring, D, and provided with a head, E, the front face of which is beveled, as shown. The spring D finds one point of resistance at 25 a, while the other is against the rear side of the head. The draw-bar is provided with three chambers, b, c, and d, the former being the largest, to allow of a horizontal motion of the head. The chamber c is smaller, but of suffi- 30 cient size to allow of the free action of the spring, while the chamber d is the smallest, being only large enough to allow the rod C to have a free reciprocating movement. The three chambers in the draw-bar are formed by the draw-bar proper, B, and the filling-sec- 35 tions e and f, which have chambers of different diameters. The sections e and f also serve to confine the guide-plate a in its proper position for receiving the end pressure of the spring D. The face of the head is beveled to 40 the rear from top to bottom, and adapted to hold the link F in a horizontal position when inserted and held in place by the pin G.

In practice one end of the link is inserted, which crowds the head back, overcoming the resistance of the spring, until the pin-hole in 45 the head is disclosed. This allows the pin, which has been sustained upon the head, to drop and pass through the end of the link. The resistance or pressure of the spring forces 50 the bend of the link against the pin at the lower end of the beveled face of the head, the upper end of said bevel overhanging the top of the link, and holding the same in a horizontal position ready to enter a similar head and draw-bar on an adjoining car with which 55 it is desired to couple. The link entering such head forces back a similar rod with its head, which is forced backward until the pin will drop and engage with the opposite end of the link, when the coupling is completed without 60 the necessity of any one going between the cars to guide the link, as in couplings of ordinary construction.

What I claim as my invention is—

1. A draw-bar, B, having an opening of the 65 same size throughout for receiving two separate hollow sections, e f, forming three chambers, b c d, of different sizes, adapted to receive the rod C, spring D, and head E, in combination with the hollow sections e f, rod C, spring 70 D, and head E, substantially as and for the purpose specified.

2. In combination with the head E, spring D, rod C, and draw-bar B, provided with sections e f, as described, the guide-plate a, se- 75 cured in the draw-bar by said sections e f, and forming a stop for the end of the spring D, and limiting the outward movement of the rod C and head E, substantially as and for the purpose specified.

WM. E. THOMPSON.
